Simon E. Theus
INVENTOR

UNITED STATES PATENT OFFICE.

SIMEON E. THEUS, OF SAVANNAH, GEORGIA.

DESIGN FOR A BADGE.

SPECIFICATION forming part of Design No. 29,611, dated November 8, 1898.

Application filed September 6, 1898. Serial No. 690,376. Term of patent 7 years.

To all whom it may concern:

Be it known that I, SIMEON E. THEUS, a citizen of the United States, residing at Savannah, in the county of Chatham and State of Georgia, have invented and produced a new and original Design for Badges, of which the following is a specification, reference being had to the accompanying drawing.

The drawing is a plan view of a badge, showing my new design.

As shown in the drawing, the leading or material feature of my design consists of a wreath around a flag, the wreath tied with a ribbon at the bottom, space being afforded in each

fold of the ribbon for any suitable words or dates.

The flag consists of three horizontal stripes of equal width, with a field in upper left-hand corner with thirteen five-pointed stars therein.

Having described my invention, what I claim as new, and desire to secure by Letters Patent, is—

The design for a badge, as herein shown and described.

SIMEON E. THEUS.
